UNITED STATES PATENT OFFICE.

LEO JOHN BAYER, OF ST. LOUIS, MISSOURI.

SOOT BLOWER.

Application filed May 8, 1922. Serial No. 559,280.

To all whom it may concern:

Be it known that I, LEO JOHN BAYER, a citizen of the United States, residing at St. Louis, State of Missouri, have invented certain new and useful Improvements in Soot Blowers, of which the following is a specification.

The present invention relates to improvements in soot blowers or boiler cleaners, particularly applicable to the Stirling water-tube type of boiler, or other boilers having tubes vertical or substantially so. The soot blower comprises a series of blower units disposed at selected points in the boiler so as to most effectively dislodge soot accumulations, and the respective units are independently operated or controlled, the construction of these units being the subject matter of the present invention.

The principal objects sought by the present improvements are to provide a soot blower unit wherein the operating valve which admits steam from the supply pipe to the blower pipe is actuated directly from the drive-shaft which actuates the revolving blower pipe; one wherein the valve is controlled so as to remain open during the period that the blower pipe is rotated through its predetermined blowing arc irrespective of the direction of rotation of the blower pipe; one wherein the operating valve is controlled by a suitable cam which may be readily replaced by a cam of different contour to vary the blowing arc of the blower pipe; one having its supply pipe flexibly supported from the boiler wall to allow for contraction and expansion of said supply pipe.

Further objects and advantages of the blower units will be better apparent from a detailed description of the invention in connection with the accompanying drawings, in which—

Figure 1 represents a side elevation of a Stirling boiler and setting showing the several banks of circulating water-tubes and baffles, side walls of the setting being removed, and the remaining walls shown in section, and the blower comprising the units of the present improved type being shown in elevation; Fig. 2 is a combined side elevation and section of the head end of the second blower unit, the side wall of the setting being shown in section, and parts being broken away; Fig. 3 is a side elevation of the opposite end of the second blower

unit, the side wall of the setting and the tubes being in section; Fig. 4 is an enlarged view of a part of the blower pipe and its jacket, parts of two adjacent sections being shown, and part of one section being broken away; Fig. 5 is a longitudinal section through the blower pipe and jacket taken along the plane of the nozzles; Fig. 6 is a vertical cross-section taken on the line 6—6 of Fig. 4; Fig. 7 is an enlarged vertical longitudinal section through the head of the blower unit; Fig. 8 is a front elevation of the blower head with parts broken away; Fig. 9 is a vertical cross-section taken on the line 9—9 of Fig. 7; Figures 10 and 11 are enlarged detail views of the valve and actuating mechanism therefor; Fig. 12 is a detached face view of the ring that is interposed between the wall sleeve and supporting bracket of the blower unit; Fig. 13 is a vertical cross-section taken on the line 13—13 of Fig. 7, and shows the intake end of the blower pipe; Fig. 14 is a vertical cross-section taken on the line 14—14 of Fig. 7, and shows the intake end of the air jacket; Fig. 15 is a side elevation of the first blower unit, a part being broken away, and parts being shown in section; Fig. 16 is an enlarged vertical cross-section taken on the line 16—16 of Fig. 15; and Figures 17 and 18 are detail views of a modified form of valve actuating mechanism.

Referring to the drawings, F represents the boiler setting, B the fire box, 1, 2, 3, the front, middle, and rear shells for steam-and-water respectively, 4 the mud drum, 5 the front bank of circulating water-tubes connecting the shell 1 with the mud drum, 6 the middle bank of water-tubes, 7 the rear bank of water-tubes, 8 the steam tubes connecting the front and middle shells, 9 the steam tubes connecting the middle and rear shells, 10 the water circulating tubes between the shells 1 and 2, and 11 the tiling or baffle directly over the tubes 10. The front baffle 12 carried by the rear members of the front bank of tubes is provided with a shelf 13 at a point below but adjacent to the upper end of the baffle, the middle baffle 14 disposed along the rear of the middle bank of tubes reaching from the shell 2 to a point near the bottom of said bank and above the mud drum, and the baffle 15 rearward of the rear bank of tubes 7 closing the opening between said bank and the rear wall of the boiler setting, all as fully understood in the art.

In the present embodiment of my invention I provide the middle baffle 14 at an intermediate point of its height with a rearwardly projecting shelf 14' above which the 5 fourth blower unit of the present improvement is installed. The arrows in Fig. 1 represent the general course of the furnace gases and combustion products, the same traveling from front to rear and making practically 10 four passes, as clearly apparent from the drawings.

The several blower units herein may be referred to as No. 1, No. 2, No. 3, No. 4, and No. 5, according to their positions in the 15 boiler from front to back in the line of flow of the gases, and vary somewhat in construction, since Nos. 1 and 2, being in the hottest part of the boiler, are air-cooled, while Nos. 3, 4, and 5 are not subject to such 20 high temperatures, and need not necessarily be provided with cooling means. Then again, blower unit No. 1, located on the bridge-wall, may or may not be provided with a revolving blower pipe, the blower 25 pipes of all the other units, however, being revoluble.

Since unit No. 2 embodies all of the features of the present invention, both for revolving the blower pipe and for cooling the 30 same, this unit will be first described. P represents the steam or cleaning-fluid supply pipe, dry steam being the usual fluid employed as well understood in the art.

The boiler side wall F is provided with 35 an opening O below the tubes 10, and a wall sleeve 16 is fitted tightly into this opening, said sleeve having a square flange 16' on the outer end into the corners of which is bolted a supporting bracket 17 for the blower 40 head H about to be described. Blower unit No. 2 is provided with a blower pipe 18 supported at the outer end in the head H, said blower pipe being confined in a jacket or air pipe 19 spaced therefrom, the assembled blower pipe and sleeve being supported 45 at suitable points along its length by brackets 20 suspended from the tubes 10. One end of the jacket 19 is open to the atmosphere, terminating in a spider 21 mounted on the blower pipe 18, the openings o between the ribs of the spider permitting air 50 to enter the jacket freely and circulate about the blower pipe, finally discharging through a riser 22 to the flue S, said riser being connected by a swivel 23 to the jacket. However, there are other ways of inducing an air 55 circulation through the jacket 19, and I do not wish to be restricted to that shown herein. Owing to the great heat in the boiler in 60 the vicinity of unit No. 2, the air circulation through the jacket 19 is of itself insufficient to keep the jacket cool enough to prevent warping. I therefore build the jacket 19 in 65 sections a, a, etc., each section being connected (by a sliding fit) to the adjacent sec-

tion by an internal sleeve 24, a slight clearance X being provided between the sections a to permit of expansion under heat (Figures 4 and 5). By virtue of this construction 70 expansion and contraction of the jacket is compensated for and buckling and warping of the unit does not take place, since any tendency in this regard in one section would be counteracted by another section, and the effect could not be cumulative, the 75 sections acting independently.

The jacket 19 is maintained in spaced relation with the blower pipe 18 by radially disposed studs 25 screw-threaded through the sections a into sliding contact with the blower pipe 18, the studs in any one plane being 90° apart and distributed in alinement and equally spaced along the jacket. Opposite to one row of studs are the nozzles 26 adapted to discharge steam into the bank of tubes 10, each nozzle being screw-threaded into the blower pipe 18 and having an intermediate polygonal enlargement 26', the inner surface of which bears against said pipe, and the outer surface of which is contoured to bear snugly against the inside of the jacket 19. The discharge end 26'' of each nozzle projects into an opening t in the jacket, said opening being large enough to provide clearance around the nozzle end 26'' to permit of 90 relative longitudinal movement of jacket and blower pipe, due to expansion and contraction, without shearing off the nozzle. The enlargement 26' closes the opening t 100 on the inside.

The blower pipe 18 receives steam through the blower head H which is connected to the supply pipe P by a riser 27, which terminates at the top in an elbow 28.

The blower head H comprises the actuating mechanism of the unit, and will now be described. A suitable housing 29 is provided with an annular bearing support 30 adjacent the open end of the jacket 19, said support having a boss 31 formed on its upper surface, and a fork 32 projecting downwardly from its lower surface, the former carrying a stud 33, and the latter forming one member of a universal joint J, the other member 34 being formed on the upper end of a pin 35. The stud 33 projects upwardly through a laterally disposed slot s formed in a lug 36 projecting outwardly from the bracket 17. The pin 35 projects downwardly through an opening u in a lug 36' extending outwardly from said bracket and directly beneath the lug 36, and a cushion spring 37 is coiled about pin 35 between joint J and the lug 36'. By virtue of the universal joint J and the connection of the slot s and stud 33 the header H is flexibly connected to the rigid bracket 17, and is freely movable both vertically and laterally relative to the bracket responsive to expansion and contraction of the riser 27 or other stresses put 130

upon the unit. Consequently any change in the relative position of the respective parts of the blower unit due to the trying conditions under which it must function are 5 compensated for, thus avoiding distortion and strain.

The blower pipe 18 is supported on roller bearings 38 within the bearing support 30 and is provided with a ball-end-thrust bearing 39 confined between the roller bearings and shoulder ν in the support 30. As the pipe 18 moves in and out under contraction 10 and expansion the header H moves with it, yielding to the necessary degree in the bracket 17.

A gear housing h is connected to the bearing support 30, the front wall 40 of the housing being bolted to it by bolts b , b , etc., a stuffing box c provided with a packing d , 20 and gland e , adjoining the housing wall. The intake end of the blower pipe 18 is surrounded by a casing 41 formed integral with the stuffing box c , said casing having a depending vertical leg 42 and a front cover 25 plate 43 through which extends a pintle 44 carrying a pointer 44' on its front end, the opposite end being screw-threaded over the end of pipe 18. A stuffing box 46 is provided on the outside of the cover plate 43 to 30 prevent steam from leaking out of the casing 41.

A drive shaft 47 is mounted in the outer wall of the hollow leg 42 and housing h , traversing the housing wall 40 and inner 35 wall of the leg 42 in which is a stuffing box 48. That part of the shaft 47 within the leg 42 carries a double worm 49 meshing with a worm-wheel 50 freely rotatable on a shaft 51 extending across the leg 42, and the part 40 of the shaft 47 within the housing h carries a pinion 52 meshing with a gear wheel 53 within the housing and set-screwed to the blower pipe 18, a pulley 54 being keyed to the drive shaft between the leg 42 and housing h . A pair of cams 55, 55 of identical 45 shape are set-screwed (or otherwise secured) to the hubs of the worm-wheel 50, each cam having opposite surfaces m , m of long radius and opposite surfaces n , n of short radius 50 joined with the surfaces m , m , and a pair of rollers 56, 56, mounted on the top of a valve cage 57 are adapted to ride over the surfaces m , n , of the cams. The lower part of the cage is provided with a valve 58 from 55 which depends a stem 59 operable in a guide 60 formed in the elbow 28 screwed into a flange 61 terminating the leg 42. A valve seat 62 is formed at the base of the flange 61 on which the valve 58 is normally seated by 60 the tension of a spring 63 coiled about the valve stem 59 and confined between the guide 60 and valve.

The ratio of pinion 52 to gear 53 is 1 to 5, and the ratio of worm 49 to worm-wheel 50 is 1 to 10, consequently when the shaft 47

is rotated in either direction, by pulling on a chain 64 passed over pulley 54, five revolutions of the pulley will impart one revolution to the blower pipe 18, and one-half revolution to the cams 55. Therefore, when 70 the blower is to be operated, it is rotated from its normal position (Figures 2, 7, and 8) through one complete revolution, the cams at the same time being rotated through a half revolution, or from low surface n 75 to opposite surface n , during which half-turn the valve 58 will be opened and steam admitted to pipe 18, since the rollers 56 must pass over one high surface m intermediate the two low surfaces n . The pointer 80 44' indicates to the operator the position of the nozzles 26 which are in line with the pointer. The steam on entering the blower pipe past the open valve 58 will discharge from the nozzles 26 throughout the period 85 that the valve rollers 56 are riding on the surfaces m . Since a half revolution of the cams is equal to a complete revolution of the blower pipe, a cam surface m equal to a 60° 90 arc will permit steam to blow from the nozzles through a 120° arc of rotation of the blowing pipe. In this case it may be said that the blower has a 120° blowing arc 95 since the supply valve is completely open during this period. Of course, some steam will be discharged from the nozzles during the period that the valve is passing from closed to open position, or vice versa, but this is immaterial. Obviously, for blower units requiring a blowing arc of more or 100 less than 120°, the cams 55 may be replaced by others wherein the surfaces m and n are of the proper length to meet the different requirements.

It will be observed that the pulley 54 may 105 be rotated in either direction for operating the blower since the operating mechanism is constantly in operative condition, and there are no impinging parts or stops such as have heretofore been used on blowers of this 110 general character. This is a very desirable feature since boiler room accessories sometimes encounter pretty rough handling. Furthermore all the working parts are encased so that they are protected from dirt or other 115 foreign matter. Then, again, the valve being actuated directly from the drive shaft by gearing as is also the pipe 18, the valve and pipe are bound to operate synchronously 120 and positively.

To prevent cold air from entering the boiler between the jacket 19 and sleeve 16, I provide an annular recess r in the bracket 17, and a ring 65 is placed in this recess, said ring having a close sliding fit with the jacket, and a series of spring clips 65' are secured to the ring in spaced relation, said clips maintaining the ring against the wall sleeve 16 and closing the opening about the jacket. 130

Blower unit No. 1 (Figures 15 and 16) likewise being in a very hot part of the boiler, has its blower pipe 18' surrounded by a jacket 19' connected by a riser 66 with the flue S to provide for a circulation of air around the blower pipe, but instead of being supported from the boiler tubes the unit is supported in saddles 67 on the bridge-wall W and in spaced relation thereto to prevent the conduction of heat to the unit from the bridge-wall. In the present instance the unit is stationary (consequently no blower head is necessary) and the blower pipe 18' is connected directly to a short riser 68 in which is a steam supply valve 69 for independently controlling the blowing operation, the riser 68 being connected to the steam supply pipe P. In other respects this unit is the same as No. 2, and if desired may be provided with a head for rotating the blower pipe.

Units No. 3, No. 4, and No. 5 are similar in all respects to unit No. 2 except that the jacket 19 is dispensed with since these units are more rearward in the boiler, and are not subjected to such excessive heat. However, I reserve the right to provide any of these units with jackets for air circulation if at any time it is desirable.

In Figures 17 and 18 I show a modified form of cam 55' for actuating the valve 58, said cam comprising a housing 70 mounted on a single worm 71, the housing having teeth 72 formed on its inner surface for engaging with the worm thread. The worm is so pitched that five revolutions thereof will carry the housing from one side of the leg 42 to the other, in its passage the cam surface 73 depressing the roller 74 and, of course, opening the valve. Of course, for the next operation the worm would have to be re-

volved in the opposite direction when the operation is repeated.

Obviously the invention is susceptible to other modifications, all of which cannot be described, and I do not wish to be understood as restricting myself to the construction herein shown.

Having described my invention, I claim:

1. In a soot blower for boilers, the combination with a steam supply pipe terminating at one end in a head, of a peripherally ported blower pipe revolvably supported at one end in the head, a valve in said head for controlling the steam flow from the steam pipe to the blower pipe, a gear wheel fixed on the blower pipe, a drive shaft, a pinion on one end of the drive shaft and meshing with said gear wheel, a worm on the other end of the drive shaft, a worm wheel meshing with said worm, and a cam fixed to the worm wheel for actuating the aforesaid valve on revolving the drive shaft.

2. In combination with a boiler and setting therefor, a soot blower unit comprising a blower pipe, a steam supply pipe therefor, an operating head communicating with the blower pipe and supply pipe, and means for securing the soot blower unit to the boiler wall comprising a wall plate having an opening for receiving the blower pipe, a pair of spaced, vertically aligned lugs projecting from said wall plate, and means for flexibly connecting the operating head to the wall plate comprising a universal joint arranged between the head and the bottom lug and a pin and slot connection between the head and the upper lug.

In testimony whereof I hereunto affix my signature.

LEO JNO. BAYER.
